Primary Examiner — Cynthia Underwood(74) *Attorney, Agent, or Firm* — Knobbe, Martens, Olson & Bear, LLP(57) **CLAIM**

The ornamental design for a bottle, as shown and described.

DESCRIPTION

FIG. 1 is a perspective view of a bottle according to the present design;

FIG. 2 is an exploded perspective view of FIG. 1;

FIG. 3 is a front elevational view of FIG. 1;

FIG. 4 is a left-side elevational view of FIG. 1;

FIG. 5 is a right-side elevational view of FIG. 1;

FIG. 6 is a top-plan view of FIG. 1; and,

FIG. 7 is a bottom-plan view of FIG. 1.

The broken lines are included for illustrative purposes only and form no part of the claimed design.
